BALANCING OF RECIPROCATING ENGINES

William Hamilton Purdie, Sunderland, England,
assignor to William Doxford & Sons Limited,
Sunderland, England, a British company

Application September 18, 1943, Serial No. 502,914
In Great Britain September 22, 1942

3 Claims. (Cl. 123—51)

This invention relates to improvements in the balancing of reciprocating engines, and has for its object to provide for balancing the scavenging-pumps of opposed-piston oil-engines of the multi-cylinder single-crankshaft vertical type, having an even number of cylinders with one scavenging pump driven direct from the crankshaft and situated at the centre of the group of cylinders. It is particularly applicable to, but not limited to, engines with four or six cylinders.

In opposed-piston engines of this type, each cylinder is served by a group of three cranks of which the middle one is connected to the lower piston in the cylinder, and the two outer cranks, which are 180° from the middle crank, are connected to the upper piston; further it has been customary to arrange the strokes of the upper and lower pistons in inverse proportion to the reciprocating weights so that the primary vertical forces for each individual cylinder are balanced. The secondary vertical forces and couples for the working cylinders are balanced collectively by suitable crank sequence, such for example, as 1—3—2—4 for four-cylinder engines with cranks equally spaced 90° apart, and 1—4—2—6—3—5 for six-cylinder engines having cranks equally spaced 60° apart. The revolving parts of the crankshaft and connecting rods of the working cylinders are so proportioned that there are no unbalanced forces for each individual cylinder, and therefore no collective force or couple for the complete engine.

When a single-piston scavenging-pump is fitted at the centre of the engine, unbalanced primary and secondary forces are introduced. It is well known that the unbalanced forces due to the revolving parts of such pump, viz.: the connecting rod, the crankpin and crankwebs, can be reduced to zero by the addition of suitable balance-weights on the crankwebs, but any further reduction of the vertical unbalanced primary force by the adoption of larger balance-weights introduces an unbalanced horizontal force which may be undesirable.

Since the centre crankpins of the pairs of working cylinders situated at equal distances on either side of the scavenging pump are 180° to each other to secure collective balance of the unbalanced secondary couples due to these cylinders, it has been proposed to secure balance of the scavenging pump by placing the scavenging pump crankpin in line with any one of the centre crankpins, and adjusting the reciprocating weights of two cylinders only, in the following manner. Assuming that the stroke of the scavenging-pump is

equal to the stroke of the lower pistons the reciprocating weight of the lower piston in phase with the scavenging-piston is reduced by 50% of the reciprocating weight of the scavenging-pump parts, and the reciprocating weight of the cylinder the centre crankpin of which is at 180° to the scavenging-crank is increased by a similar amount; the unbalanced vertical primary force due to the scavenging piston assembly will thereby be reduced to zero, and no primary unbalanced vertical couple will be introduced.

If the scavenging-pump stroke differs from the lower piston-stroke, the amounts by which the piston reciprocating weights are increased or decreased will require modification in direct proportion to the ratio of the scavenging-pump stroke to the lower piston-stroke.

If the reciprocating weight of the scavenging-pump is considerable, however, the necessary reduction in the reciprocating weight of the one lower piston may be impracticable, and the necessary additional weight required to be added to the other piston may be larger than can be accommodated conveniently—say inside the piston-skirt. Moreover, the increased weight necessitates heavier lifting-gear for assembly and overhauling purposes, and in a multi-cylinder engine three types of the lower piston assembly would be necessary, viz.: normal, light and heavy, so that additional spare parts are required. Furthermore, the heavy out-of-balance forces thereby acting on individual cylinders cause considerable bending stresses in the engine-structure.

According to the present invention, the reciprocating weights of all the lower (or upper) pistons of the working cylinders are modified, half of the number being increased and the other half decreased, all by the same amount, and the position of the scavenging crank is arranged relatively to the other cranks so that the unbalanced primary vertical and horizontal forces and couples for the complete engine remain at zero, whilst the unbalanced secondary vertical forces and couples are reduced to unimportant values.

According to another feature of this invention, the scavenging crank is spaced centrally in a consecutive group of half the total number of cranks, and the lower pistons of said group of cranks are reduced in weight by equal amounts, which amounts are such that, taking into account their phase relationship, they are jointly equivalent to half the weight of the scavenging-pump assembly, and the remaining lower pistons are increased in weight by the same equal amounts.

In the accompanying drawings:

Figure 1 is a more or less diagrammatic sectional elevation showing one construction and arrangement of a cylinder unit of one type of engine to which the invention may be applied,

Figure 2 is a purely diagrammatic view illustrating the application of the invention to a four-cylinder engine.

Figure 3 is a crank sequence diagram of the engine of Figure 2,

Figure 4 is a diagram showing the application of the invention to a six-cylinder engine, and

Figure 5 is a crank sequence diagram for the engine illustrated in Figure 4.

Referring first to Figure 1, the reference 10 indicates a cylinder having a lower piston 11 and an upper piston 12 which are reciprocated in opposition to one another. Each such cylinder of the engine is served by a group of three cranks on a crankshaft 13, whereof the middle crank 14 is connected to the lower piston 11 and the two outer cranks 15 which are disposed at 180° from the crank 14, are connected through suitable side rods to a cross-head 16 connected by the rod 17 to the upper piston 12. The two pistons 11, 12 therefore move in opposition to one another and they may have equal strokes, or as illustrated, the lower piston 11 may have a longer stroke than that of the upper piston 12. Suitable ports for the inlet of scavenging and combustion air and for the delivery of the exhaust are controlled by the pistons, and the fuel is injected by a suitable nozzle indicated at 18. The balancing of one cylinder unit of the engine is ordinarily effected by making the reciprocating weights for the two pistons equal, if they have strokes of the same length, or to make the weights in inverse proportion to the strokes if the latter are of different length. This description is given merely by way of example of one construction of engine to which the invention may be applied.

Turning now to Figure 2, there is illustrated diagrammatically a four-cylinder engine in which the cylinders are numbered respectively, No. 1, No. 2, No. 3, and No. 4 and each is provided with two pistons coupled to a single crankshaft indicated generally by the reference 19.

A reciprocating scavenge-pump arranged at the middle of the row of cylinders is constituted by a cylinder 20 with a piston 21 driven from the crankshaft 19 by a crank 22. Balance weights 23 may be provided for the crank 22 to give revolving balance.

For such a four-cylinder engine, a suitable crank sequence or firing order is 1-3-4-2 as shown in Figure 3, this diagram referring to the centre crank for each cylinder unit. In this particular example, the pistons whereof the weight is modified to effect balancing in accordance with this invention, are the lower pistons of the four cylinders indicated at 24, 25, 26 and 27 respectively, and the reciprocating weight of the scavenge-pump 20, 21 is balanced by reducing the weights of two of the lower working pistons and increasing the weight of the other two. For this purpose the crank 22 of the scavenge-pump is set at the position SP in Figure 3 mid-way between the centre cranks of No. 3 and No. 4 cylinders, these being two consecutive cranks in the crank sequence diagram. The reciprocating weights of the pistons 26 and 27 for the cranks No. 3 and No. 4 are reduced, conveniently by fitting thinner piston-skirts to those pistons or in any other convenient manner, and the pistons 24 and 25 for No. 1 and No. 2 cylinders have

their weight increased by the same amount. Owing to the phase displacement of the cranks, the weight which has to be added to or subtracted from the working pistons to achieve this balance is equal to $\frac{1}{4}\sqrt{2}=0.353$ of the reciprocating weight of the scavenge-piston assembly, when the stroke of the scavenge-piston is equal to that of the lower pistons. If its stroke be greater or less than that of the working pistons the amount to be added or subtracted will be greater or less in proportion to the respective strokes.

In Figure 2 therefore the pistons 26 and 27 have their weight reduced by providing thinner skirts as mentioned above and the pistons 24 and 25 have their weights increased by means of suitable masses 28, 29 which may be secured inside the skirt, or disposed in any other convenient manner. It is a convenience from the point of view of carrying spares, that the four pistons 24, 25, 26, 27, should all be identical with one another and the masses 28 and 29 should be separate and attachable at will, so that only one kind of spare piston need be carried for all the lower working pistons.

Figure 4 is a diagram similar to Figure 2 showing one mode of applying this invention to a six-cylinder engine. The various cylinder units are marked Nos. 1 to 6 and a suitable crank sequence for such an engine is shown in Figure 5, as 1-4-2-6-3-5. In Figure 4 the crankshaft is indicated generally by the reference 30 and the scavenge-pump 31 is situated at the middle of the length of the engine between cylinders No. 3 and No. 4. Its crank 32 is shown as giving it a stroke equal to that of the lower working pistons of the cylinders and it is arranged, as above described, centrally in the consecutive group of cranks 3-5-1, so that its angular disposition is the same as that of crank No. 5.

In order to effect the balancing of the scavenge-pump, the pistons of this group have their weight reduced and the pistons of the other group 4-2-6 have their weight increased by the same amount. Owing to the phase relationship of the cranks of the various cylinders, the amount which is subtracted from each of the pistons 3, 5, 1, and the amount which is added to each of the pistons 2, 4, 6, is equal to one quarter of the reciprocating weight of the scavenge-pump assembly when the stroke of the scavenge-pump is the same as that of the lower piston. If the stroke is greater or less than that of the lower pistons, the amount to be added or subtracted will be greater or less in proportion as before. The details of construction mentioned above in describing Figure 2 apply equally to the six-cylinder engine and therefore need not be repeated.

In both of the above examples, the modification of the weight of the pistons to effect balancing of the scavenge-piston has been described as applied to the lower working pistons in the cylinders, but it will be appreciated that it could equally well be applied to the upper set of pistons; it will also be appreciated that, if desired, the modification of weight could be applied to both the upper and lower working pistons, but ordinarily this will not be preferred as it will increase the out-of-balance forces for the individual cylinders.

The advantages of this invention are as mentioned above, that elimination of the primary vertical and horizontal unbalanced forces or couples for the complete engine is obtained, together with the reduction of the unbalanced secondary vertical forces and couples to unimportant values,

whilst still retaining the working parts of all the cylinders duplicates of one another. Moreover, the modification in weight to increase or decrease the weight of the different parts being distributed over a large number of cylinders, comes within a practicable range and does not require any substantial increase in the lifting capacity of the overhauling gear. The individual out-of-balance forces for the various cylinders are smaller than with the previously known methods of balancing the scavenge-pump, so that the bending stresses on the engine structure are reduced.

I claim:

1. In an oil engine of the vertical, multi-cylinder, opposed-piston, single crankshaft type, the combination of a plurality of working cylinders, a reciprocating scavenge-pump at the middle of the row of cylinders, a set of upper pistons in said cylinders, a set of lower pistons in said cylinders, whereof the weight of one half of one set of pistons is increased and the weight of the other half is decreased all by the same amount, and the position of the crank for the scavenge-pump is arranged relatively to the cranks of the said pistons so that the unbalanced primary vertical and horizontal forces and couples for the complete engine are maintained at zero and the secondary ver-

tical forces and couples are reduced to unimportant values.

2. In an oil engine of the vertical, multi-cylinder, opposed-piston, single crankshaft type, the combination of a plurality of working cylinders, a set of lower pistons and a set of upper pistons in said cylinders, sets of angularly spaced cranks connected to said sets of pistons respectively, a reciprocating scavenge-pump situated at the middle of the row of cylinders, a separate crank for the scavenge-pump spaced centrally in a consecutive group of half the total number of cranks of one set of pistons, the pistons of said set being reduced in weight by equal amounts, which amounts are such that, taking into account their phase relationship, they are jointly equivalent to half the reciprocating weight of the scavenge-pump assembly, and the remaining pistons of said set are increased in weight by the same amount.

3. In an oil engine of the vertical, multi-cylinder, opposed-piston, single crankshaft type according to claim 1, the combination with the set of pistons whereof the weights are to be modified, which pistons are all of the minimum weight, of detachable additional weights and means for securing them to said pistons.

WILLIAM HAMILTON PURDIE.
